POWER-DRIVEN POSTHOLE DIGGER

George Herbert Haines, Caledonia, Ohio, assignor
to Turner of Indiana, Indianapolis, Ind., a cor-
poration of Indiana

Application May 3, 1946, Serial No. 667,174

7 Claims. (Cl. 255—19)

1

This invention relates to a power driven post hole digger and has for a primary object the high speed digging of holes with a positive lifting of the dirt from the hole and depositing of that dirt in a pile to one side of the hole.

Other objects and advantages of the invention reside in the unique construction of the device permitting quick and easy alignment of holes and giving a high degree of durability, all at a relatively low cost of production.

These and other advantages and objects of the invention will become apparent to those versed in the art in the following description made in reference to the accompanying drawings in which

Fig. 1 is a view in side elevation of the structure embodying the invention;

Fig. 2, a top plan view;

Fig. 3, a bottom plan view;

Fig. 4, an elevation of the reverse side from that shown in Fig. 1;

Fig. 5, a view in rear elevation;

Fig. 6, a detail on an enlarged scale in vertical section of the lower end of the auger and tube;

Fig. 7, a detail in vertical elevation and section of the auger driving means;

Fig. 8, a horizontal section on the line 8—8 in Fig. 1;

Fig. 9, a horizontal section on the line 9—9 in Fig. 1;

Fig. 10, a view in discharge side elevation of a slightly modified form;

Fig. 11, a view in side elevation of that modified form;

Fig. 12, a view in rear elevation of that form;

Fig. 13, a detail in section on the line 13—13 in Fig. 11;

Fig. 14, a view in side elevation of a still further modified form;

Fig. 15, a view in rear elevation of the form shown in Fig. 14;

Fig. 16, a top plan view;

Fig. 17, a detail in section on the line 17—17 in Fig. 14; and

Fig. 18, a detail in vertical section on the line 18—18 in Fig. 14.

Like characters of reference indicate like parts throughout the several views in the drawings.

First referring to that form of the invention as shown in Figs. 1-8, a cylindrical tube 20 is mounted to slide vertically between a pair of guide rails 21 and 22 on one side and a pair of like guide rails 23 and 24 on the other side. The diameter of this tube 20 is selected to be substantially equal to the diameter of the hole to be dug. Also, the length of the tube 20 is made to exceed the depth of the hole to be dug.

The pairs of rails 21, 22 and 23, 24 are fixed between a lower mounting frame 25 and a top frame 26. The tube 20 is provided with a lug 27 to slide between the rails 21 and 22, and is also

provided with a like lug 28 to slide between the rails 23 and 24. The upper end of the tube 20 is provided with a lateral extension 29, from the outer end of which extends a spout 30.

5 On the back side of the tube 20 at the top end thereof are a pair of upwardly extending brackets 31 and 32, fixed in position on the tube 20 and carrying across their top ends a plate 33 fixed thereto. A shaft 34 is rotatably supported by this plate 33 to hang vertically therefrom and to extend downwardly centrally into the tube 20. About this shaft 34 is a conveyor member in the nature of an auger 35 which extends downwardly to the lower end of the tube 20 to carry a cutting edge 36 slightly therebelow, Fig. 6.

On the upper end portion of the shaft 34 is fixed a sprocket 37, Fig. 8. A chain 38 engages around the sprocket 37 to extend horizontally therefrom and around a sprocket 39 through which a drive shaft 40 extends. The two shafts are maintained in fixed spacing apart one from the other by means of the plate 33 and also a top plate 41 fixed to the plate 33 by any suitable means, such as by the bolts 42 and 43 interengaging those plates through spacers 44 and 45. The shaft 40 may have any suitable driving connection desired between it and the sprocket 39 which will permit the sprocket 39 to slide longitudinally along the shaft 40 and be driven by the shaft 40 at any position therealong. In the present form, Fig. 7, the shaft 40 is made to be square in cross section to fit slidingly through a square hole in the sprocket 39. The sprocket 39 is provided with upper and lower bosses 46 and 47 respectively to extend into or through the plates 33 and 41 as a means of maintaining the sprocket 39 in a fixed spacing from the sprocket 37, the shaft 34 being rotatably carried through the plates 33 and 41.

40 The shaft 40 extends upwardly through the top frame 26 to have a bevel gear 48 fixed to its top end and in constant mesh with gears 49 and 50 fixed respectively to the horizontal shafts 51 and 52 carried across the frame 26, one shaft in alignment with the other. The shaft 40 extends downwardly to a gear housing 53 through which the shaft 40 is driven in the present showing by a horizontally disposed shaft 54 that may be connected with any suitable source of power. Thus, the shafts 51 and 52 are driven, one in the opposite direction from the other by the shaft 40. This shaft 40 also in turn drives through the chain 38 the auger shaft 34. By reason of the mounting of the sprocket 39 to slide along the shaft 40, the tube 20 may be raised and lowered to have the auger shaft 34 driven at any shifted position of the tube 20.

55 Mounted across the lower frame 25 are shafts 55 and 56 to have the tube 20 extend downwardly therebetween. Fixed respectively to these

shafts 55 and 56 are spur gears 57 and 58. These spur gears 57 and 58 are in constant mesh with rack gears 59 and 60 that are fixed to the sides of the tube 20. In the form herein shown, these rack gears 59 and 60 consist essentially of perforated bars with circular holes 70 therethrough to receive the teeth therein of the gears 57 and 58. Preferably the wall of the tube 20 is perforated to match the holes 70 of the bars 59 and 60 so that dirt may pass on through those holes and not become compacted therein under pressure of the teeth of the gears 57 and 58. Also, by having the holes 70 in alignment with matching holes 71 in the tube 20, peep holes are provided to observe whether or not dirt is being elevated within the tube 20. As indicated in the drawings, the bars 59 and 60 are located substantially 90° around the tube 20 from the lugs 27 and 28. These lugs, of course, prevent turning of the tube 20 circumferentially.

On one side of the frame 25, the shafts 55 and 56 extend therefrom to have fixed thereon the intermeshing spur gears 72 and 73. The upper frame 26 is supported in fixed position spaced from the lower frame 25 by any suitable framework, herein shown as consisting essentially of the pairs of guide rails 21, 22 and 23, 24 and also a pair of rearwardly spaced posts 74 and 75 with suitable transverse cross braces 76 therebetween. A transverse shaft 77 is carried above the shaft 55 and back of the tube 20 to have a spur gear 78 in constant mesh with the gear 72. The other end of the shaft 77 carries fixed thereon a sprocket 79 which is driven by a chain 80 from a sprocket 81 fixed on a shaft 82 that is mounted across the rear sides of the posts 74 and 75.

On the ends of this shaft 82 are fixed belt pulleys 83 and 84. A belt 85 is carried around the pulley 83 and extends upwardly to be carried around a pulley 86 that is fixed to the shaft 51. The belt is mounted to have considerable slack so that normal turning of the shaft 51 does not drive the shaft 82. In the same manner a belt 87 is carried around the pulley 84 and upwardly and around a pulley 88 that is fixed on the shaft 52.

Hinged to the post 75 is a swingable arm 89. A pulley 90 is mounted on this arm 89 to bear against the rear upper flight of the belt 85 so that by pushing the pulley 90 thereagainst, the slack will be taken out of the belt 85 and from the shaft 51, the belt 85 will be driven to turn the shaft 82 accordingly but without driving the belt 87 which is in a slack condition. The arm 89 may be swung from any suitable control, such as by means of a link 91 pivotally interconnecting the arm 89 with an operating lever 92. To drive the shaft 82 in an opposite direction, the pulley 90 is swung away from the belt 85 and an arm 93, herein shown as pivoted to the post 74, is swung rearwardly to have a pulley 94 carried on the arm 93 push against the forward flight of the belt 87 and thereby take up the slack in that belt to cause the shaft 82 to be turned in the direction of rotation of the shaft 52. This arm 93 may be controlled through a link 94 connected with the lever 92, whereby swinging the lever 92 to the left, Fig. 1, will push the pulley 90 into its belt engagement and carry the pulley 94 away from the other belt. Reverse travel of the lever 92 will, of course, reverse the travel of the pulleys 90 and 94. The tube 20 and the auger therein is lowered or raised by travelling of this shaft 82. To prevent unwarranted lowering of the tube 20, such as in moving from one location to

another, the shaft 82 is provided with a brake pulley 95, around which is wrapped a flexible belt 96 to have one end fixed to a cross member 97 between the posts 74 and 75, and the other end to a lever 98, by means of which the belt 96 may be pulled tightly around the pulley 95.

As indicated in Fig. 6, a second cutting edge 99-180° from the cutting edge 36 may be employed. From the edge 99 a short section 100 of a conveyor flight is carried upwardly around the shaft 34. The lower end of the shaft 34 may be extended to any desired length below the cutting edges 36 and 99 to serve as a pilot, a short length being shown in the drawings. The lower frame 25 may be mounted upon any suitable vehicle (not shown) and stabilizing braces 101 and 102 may be employed to extend rearwardly from the posts 74 and 75 so as to maintain the entire apparatus in its vertical position.

In operation, the shaft 54 is driven and the belts 85 and 87 are normally loose so that until either pulley 88 or 94 may be shifted to tighten the respective belts, the tube 20 and its contained auger will remain in the normal upper position as indicated in the drawings. However, the auger 35 is turning at all times when the shaft 54 is turning. This operation, of course, is controlled at the power source. When the spot is located where the hole is to be dug, the tube 20 is lowered by selective use of the lever 92 and the auger 35 is allowed to start entering the earth. Dirt loosened will be carried up the auger to the lateral extension 29 at the top end. An exit is provided to guide the dirt into the spout 39 from which the dirt may fall in one direction onto a pile at one side of the hole being dug, the tube 20, of course, may be allowed to drop by gravity or even forced downwardly so that the wall of the hole is maintained. The lower cutting edges 36 and 99 extend outwardly a sufficient distance to cut a hole sufficiently large to permit the tube 20 to slide downwardly therein. By reason of the employment of the tube 20, all of the dirt loosened at the cutting edges is carried upwardly within the tube so that there is a positive elevation of the dirt rather than a simple screwing of the auger down into the soil as in the nature of a wood screw entering wood without removing or lifting the dirt.

Referring to Figs. 11-13, a slightly modified form of elevating and lowering mechanism is shown. In this form, there is a single shaft 103 carried by the lower frame 25 back of the tube 20. The tube 20 in this instance is guided between the front cross member 104 of the frame 25 and a transverse bar 105. On each of the ends of the shaft 103 are fixed respectively the sprockets 106 and 107 to carry there around the respective chains 108 and 109 which in turn are carried around sprockets 110 and 111 fixed on the outer ends of a transverse shaft 112 mounted across the top frame 26. One flight of each of the chains 108 and 109 is so positioned as to be parallel to the respective pairs of guide bars 21, 22 and 23, 24. A bracket 113 is fixed to one of the side plates of the chain 108 and 109 in each instance and secured to the respective slide members 27 and 28, whereby travel of the two chains will cause a corresponding travel of the tube 20. This attaching mechanism is best illustrated in Fig. 13.

On the outer end of the shaft 103 outside of the sprocket 106 is fixed a sprocket 114 to be driven by a chain 115 from a sprocket 116 fixed on the outer end of the shaft 82. Thus, the turn-

ing of the shaft 82 as above described will lower or raise the tube 20 depending upon the direction of travel of the shaft 82.

Referring to Figs. 14-18, a still further modified form of the driving mechanism is illustrated. In this form, the primary purpose is to eliminate as far as possible gears and sprockets from the lower end of the apparatus and confine such members to the upper portion, to the end that such members will be removed from accidental dropping thereon of dirt as may be dropped from the spout 30 or as may be carried up with the tube 20 as it is withdrawn from the hole.

In this last form, the tube 20 is shown as being partially lowered. On each side of the tube are mounted respectively chains 117 and 118 to be carried around lower sprockets 119 and 120 and upper sprockets 121 and 122 fixed on a cross shaft 123 carried on the top frame 26. The rear flight of each of the chains has a link in each instance fixed to the slide members 27 and 28 whereby travel of the chains will lift and lower the tube 20. As illustrated in Fig. 17, the chain is attached to the slide 28, for example, by means of a bolt 124 passed through the chain 117 to engage an angle bracket 125 that is in turn bolted to the slide member 28. As indicated in Fig. 18, the lower chain sprockets, for example, sprocket 119 is adjustably mounted on a bracket 126 which is secured to the lower frame 25.

The upper shaft 123 is driven by means of a chain 127 by a sprocket 128 fixed on the shaft 129 that is mounted across the posts 74 and 75 below the top frame 26. The shaft 129 in turn is driven by a chain 130 driving the sprocket 131 on the shaft 129 from a sprocket 132 fixed on the transverse shaft 133. The shaft 133 has the belt pulleys 134 and 135 respectively fixed to its outer ends. Normally, slack belts 136 and 137 are carried upwardly from the pulleys 134 and 135 to engage around the pulleys 88 and 86 fixed respectively to the outer ends of the shafts 52 and 51. The two shafts 51 and 52 are driven in opposite directions by means of the shaft 49, as above described, through the bevel gears 48 on the shaft 40 and 49 and 50 respectively on the shafts 51 and 52. In this form it is to be noted that the belts 136 and 137 are quite short in comparison to the belts 85 and 87 shown in Figs. 1-10.

In order to remove the slack from the respective belts 136 and 137, to permit selective driving therethrough, a rocker shaft 138 is mounted above the shaft 133. On this shaft 138 are mounted two arms 139 and 140, each carrying toward its outer end a belt engaging pulley 141 and 142 respectively. As indicated in the drawings, Figs. 14-16, these arms 139 and 140 are angularly displaced one from the other about the shaft 138 to have the pulley 141 on the forward side of the front flight of the belt 136, and the pulley 142 on the rear side of the rear flight of the belt 137. Thus, by suitably rocking the shaft 138, either pulley may be selectively carried against its respective belt. The rocking of the shaft 138 may be produced in any suitable manner, herein shown as through a lever 242 fixed to the shaft 138, from which lever 242 extends a link 243 downwardly to connect with the upper arm of a bell crank 144 rockably mounted on the post 74. From the lower arm of the crank 144 extends a link 145 to a lever 146 suitably mounted and located. By pushing the lever 146 to the left, Fig. 14, the pulley 141 is carried against the belt 136. Pulling the lever 146 to the right removes the pulley 141

from the belt 136 and carries the pulley 142 against the other belt 137.

It is desirable that there be upper and lower limit stops to control the travel of the tube 20. 5 In the absence of such means, the upper mechanism carrying the chain 38 might be jammed against the frame 26, or other parts which may project into its path. The same thing is true at the lower limit of travel. Referring to Figs. 14 and 15, one such limiting means is illustrated wherein an arm 175 is carried forwardly from the bell crank 144 and then bent transversely to be in the path of the underside of the plate 33 as the tube 20 may be lowered. Also, there is an arm 176 fixed to the cross shaft 138 to be in the path of the plate 41 when the tube 20 is elevated to a sufficient height. As the tube 20 may be raised toward its upper limit, the plate 41 will strike the arm 176 to carry it upwardly and thereby rock the pulley 142 away from the belt 137 and carry the pulley 141 toward the belt 136, but not into that position where the belt 136 will start driving the shaft 133. In other words, the arm 176 will rock the shaft 138 sufficiently to have both belts 136 and 137 free from driving conditions. When the tube 20 is lowered to the desired depth of hole, the plate 33 will strike the arm 175 to again rock the shaft 138 through the bell crank 144, the link 243 and the arm 242, to again place the pulleys 141 and 142 in positions to leave the belts 136 and 137 free. Of course, the spacing between the arms 175 and 176 may be varied in accordance with the amount of travel desired of the tube 20. The direction of travel of the shaft 54 will be made to be such that the arms 175 and 176 shift the pulleys 141 and 142 in the right direction corresponding to release of the belts respectively for down and up travel of the tube 20.

40 While I have herein shown and described my invention in the forms now best known to me, it is obvious that other mechanical variations may be employed without departing from the spirit of the invention, and I therefore do not desire to be limited to the precise forms as described beyond the limitations as may be imposed by the following claims.

I claim:

1. In a post hole digger comprising a tube substantially of the same diameter as that of the hole to be dug, an auger revolvably mounted in the tube and fixed against longitudinal displacement therealong, and power driven means for revolving said auger throughout the range of up 55 and down travel of the tube; power operated means for lowering and raising said tube, said power operated means comprising a pair of shafts, a driving shaft interconnecting with said pair of shafts to drive them in opposite directions, a driving connection between each of said pair of shafts and said tube, and friction means in each of said driving connections for selective operation, a jack shaft intermediate said tube and said driving connections, said connections consisting each of a normally slack belt wrapped around pulleys fixed to said jack shaft and a pulley each on said pair of shafts, drive means between said tube and said jack shaft, and means selectively tightening said belts.

2. In a post hole digger comprising a tube substantially of the same diameter as that of the hole to be dug, an auger revolvably mounted in the tube and fixed against longitudinal displacement therealong, and power driven means for revolving said auger throughout the range of up and

down travel of the tube; power operated means for lowering and raising said tube, said power operated means comprising a pair of shafts, a driving shaft interconnecting with said pair of shafts to drive them in opposite directions, a driving connection between each of said pair of shafts and said tube, and friction means in each of said driving connections for selective operation, a jack shaft intermediate said tube and said driving connections, said connections consisting each of a normally slack belt wrapped around pulleys fixed to said jack shaft and a pulley each on said pair of shafts, drive means between said tube and said jack shaft, and means selectively tightening said belts, said drive means between said jack shaft and said tube comprising an endless chain mounted along one side of the tube, means attaching said chain at a localized zone to said tube, and drive means between said chain and said jack shaft.

3. In a post hole digger comprising a tube substantially of the same diameter as that of the hole to be dug, an auger revolvably mounted in the tube and fixed against longitudinal displacement therealong, and power driven means for revolving said auger throughout the range of up and down travel of the tube; a tube carrying structure comprising a top and bottom frame held in fixed spaced relation by intermediate connecting members, said connecting members serving as tube guides to hold the tube against rotation and to direct it through said lower frame; a drive shaft revolvably carried by said structure in substantial parallel alignment with the axis of said tube and held against longitudinal shifting; a pair of shafts revolvably carried across said structure; gear means interconnecting the pair of shafts with said drive shaft to cause the shafts in said pair to be driven one oppositely from the other; a revolute member in said frame at the side of said tube engaging therewith for up and down shifting thereof; drive members normally inoperatively interconnecting between said shafts in said pair and said revolute, tube shifting member; and means selectively placing said interconnecting drive members in operative condition.

4. In a power driven post hole digger having a revolute auger inside a tube, comprising a vertically disposed frame, vertically guiding and holding said tube against circumferential travel; a power input connection at a lower part of said frame; a vertically disposed revolute shaft removed from said tube and fixed against longitudinal travel, driven from said connection and extending throughout a distance of possible vertical tube travel; said auger having an upper end driving portion at the top portion of said tube; a head frame carried by said tube top portion, extending laterally therefrom to receive shiftably therethrough said vertical shaft; a drive system carried by said head frame interconnecting said vertical shaft and said auger driving portion; a gear on the upper end portion of said shaft; a tube elevator shaft carried by said vertical frame extending laterally from the vertical shaft; a second tube elevator shaft carried by said vertical frame to extend in opposite direction to the first tube shaft from the vertical shaft; a gear on each of said tube shafts constantly meshed with said vertical shaft gear; a jack shaft carried by said vertical frame; a chain carried by said vertical frame and connected to said tube to raise and lower said tube; means interconnecting said chain with said jack shaft

whereby selective turning of the jackshaft will raise and lower the tube; a pulley shaft carried by said vertical frame; a belt normally slack, extending between each of said tube elevator shafts and said pulley shaft; driving means between said jackshaft and said pulley shaft; and means selectively tightening either of said belts into driving condition, whereby said jackshaft and hence said chain may be driven up or down.

5. In a post hole digger having a frame, a tube vertically reciprocable within said frame, an auger rotatable within and reciprocable with said tube and a drive train to said auger; means for actuating said tube comprising a pair of driving connections from said drive train to said tube and each including a drive member engaging the tube, each said driving connection being adapted for being made effective to drive the tube in a different of its up and down directions, a slack belt in each said connection, a guide pulley for tightening each belt, and arm means pivotally mounted on said frame and carrying said pulleys and having two operative positions wherein said pulleys are alternately effective for tightening their associated belts and having a third position wherein both of said pulleys are in their belt slack position.
6. In a post hole digger having a frame, a tube vertically reciprocable within said frame, an auger rotatable within and reciprocable with said tube and a drive train to said auger; means for actuating said tube comprising a pair of driving connections from said drive train to said tube and each including a drive member engaging the tube, each said driving connection being adapted for being made effective to drive the tube in a different of its up and down directions, a slack belt in each said connection, a guide pulley for tightening each belt, arm means pivotally mounted on said frame and carrying said pulleys and having two operative positions wherein said pulleys are alternately effective for tightening their associated belts and having a third position wherein both of said pulleys are in their belt slack position.

7. In a post hole digger having a frame, an auger tube guided for vertical reciprocation in said frame, an auger rotatable in and reciprocable with said tube and a drive train to said auger; vertically extending endless chains on opposite sides of said tube and sprockets in said frame supporting said chains, each of said chains being connected with said tube at one point, a pair of driving connections from said drive train to said chains and each operable for driving the chains in a different direction, and control means movable to make said driving connections selectively effective or both ineffective.

GEORGE HERBERT HAINES.
